Primary Examiner — T. Chase Nelson

Assistant Examiner — Eric Goodman

(74) *Attorney, Agent, or Firm* — Louis Woo(57) **CLAIM**

The ornamental design for a catheter adapter, as shown and described.

DESCRIPTION

FIG. 1 is a perspective view of the outer surfaces of the catheter adapter in an open configuration showing my new design;

FIG. 2 is a perspective view of the inner surfaces of the catheter adapter of FIG. 1 in an open configuration;

FIG. 3 is a perspective view of the catheter adapter of FIG. 1 in a closed configuration;

FIG. 4 is a perspective view of the catheter adapter of FIG. 1 in a closed configuration;

FIG. 5 is a plan view of the catheter adapter of FIG. 1 in a closed configuration;

FIG. 6 is a second plan view of the catheter adapter of FIG. 1 in a closed configuration;

FIG. 7 is a side view of the catheter adapter of FIG. 1 in a closed configuration, the broken line showing the catheter adapter is to illustrate portions of the article and form no part of the claimed design;

FIG. 8 is the other side view of the catheter adapter of FIG. 1 in a closed configuration, the broken line showing the catheter adapter is to illustrate portions of the article and form no part of the claimed design;

FIG. 9 is a perspective view of the inner surfaces of the catheter adapter of FIG. 1; and,

FIG. 10 is a perspective view of the outer surfaces of the catheter adapter of FIG. 1.
